UNITED STATES PATENT OFFICE

HUGH D. CLARK, OF COLUMBUS, OHIO.

FENCE-POST.

1,058,085.

Specification of Letters Patent.

Patented Apr. 8, 1913.

Application filed December 23, 1912. Serial No. 738,175.

To all whom it may concern:

Be it known that I, HUGH D. CLARK, a citizen of the United States, residing at Columbus, in the county of Franklin and State of Ohio, have invented certain new and useful Improvements in Fence-Posts, of which the following is a specification.

My invention relates to fence posts and more particularly to metallic fence posts that are adapted for ready placement in any desired location for securely but removably holding the common type of wire fence in position.

I aim to provide a type of fence post of inherent strength and rigidity and one that may be very cheaply manufactured. In the effectuation of this result, I preferably roll a piece of sheet metal to the form of an inclosure having overlapping ends not necessarily soldered or riveted in position. I aim to slot this sheet metal at intervals along its joint in a manner that by the use of a locking wire, the post is securely locked in its correct shape and at the same time the fence is also held in true vertical position.

From the foregoing, it will be apparent that my post is necessarily of a hollow construction and, when it is desired to use very thin sheet metal, this hollow portion may be filled with cement or the like to form a very rigid and substantial construction.

The preferred embodiment of my invention is shown in the accompanying drawings, in which similar characters of reference designate corresponding parts, and in which:

Figure 1 is a side elevation of my post shown in its position in the ground with the ordinary type of wire fence applied thereto, Fig. 2 is a cross section taken on line 2-2 of Fig. 1, and, Fig. 3 is a cross section taken on line 3-3 of Fig. 1.

In the drawings, my fence post is shown as comprising a body portion 1 of comparatively thin sheet metal, rolled to a substantially cylindrical form and having its ends 2 and 3 overlapping and in loose engagement with each other. I preferably bend these ends to V-shape, thereby forming a joint of a somewhat interlocking nature. The resiliency of the metal will normally

hold the post in its correct assembled position. These V-shaped protrusions are also slotted at intervals, the outside member being slotted as at 4, leaving a portion of the body metal as at 5. The inner V-shaped portion 3 is slotted as at 6 without leaving any of the body metal, for a purpose to be hereinafter described. The various strands of the wire fence 7 are inserted through these slots and are securely held in position by the provision of a locking wire 8 provided with a circular hand-hold 9 at its upper end to facilitate its ready removal and to prevent its passage to the bottom of the post. This locking wire 8 and the strands of the wire fence 7 both coöperate to securely lock the post in its assembled position, thereby obviating the necessity of soldering or riveting the joint formed by the overlapping ends. It will be noted that the V-shaped portion 4 is prevented from outward movement by the provision of the small strip of body metal 5, contacting with the strands of the fence. Likewise, the inner V-shaped portion 6 is prevented inward movement by the wire strands contacting with the inner edges of the slots in the outer V-shaped portion 4. Thus, it will be apparent that not only is the fence securely held in its applied position on the post, but also the post is prevented from collapse without the provision of a rigid joint. It will also be apparent that comparatively thin sheet metal may be used for this purpose, inasmuch as its shape is in the nature of an inclosure, which inclosure may be readily filled with cement or the like.

What I claim, is:

1. A fence post comprising a sheet metal body bent to form an inclosure and having its ends overlapping, said overlapping portions being provided with registering slots to receive the strands of a wire fence, and a locking wire adapted for placement between said wire strands and the inner surface of said post whereby the overlapping portions are securely locked together and the fence held in position.

2. A fence post comprising a sheet metal body bent to substantially cylindrical form, the free ends of said body bent to form interlocking V-shaped protrusions, said pro-

trusions having registering slots therein to receive the strands of a wire fence, and a locking wire adapted for placement between said wire strands and the inner surface of the post whereby the interlocking portions are securely locked together and the fence held in position.

In testimony whereof I affix my signature in presence of two witnesses.

HUGH D. CLARK.
